SHIP

Thomas Boyle, Detroit, Mich.

Application May 10, 1943, Serial No. 486,353

1 Claim. (Cl. 114—43.5)

The present invention relates to new and useful improvements in ships for use particularly in time of war, and has for its primary object to provide a vessel of this character comprising unique means for carrying and expeditiously and safely launching a plurality of small but swift and powerful protective or life boats.

Another very important object of the invention is to provide a ship of the aforementioned character which embodies novel means for recovering the boats.

Other objects of the invention are to provide a ship of the aforementioned character which will be comparatively simple in construction, highly efficient in operation, seaworthy, and which may be produced at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a ship constructed in accordance with the present invention.

Figure 2 is a fragmentary view in horizontal section, taken substantially on the line 2—2 of Figure 1.

Figure 3 is a fragmentary view in vertical longitudinal section, taken substantially on the line 3—3 of Figure 2.

Figure 4 is a cross sectional view, taken substantially on the line 4—4 of Figure 3.

Figure 5 is a cross sectional view through the crane.

Referring now to the drawings in detail, it will be seen that the embodiment of the invention which has been illustrated comprises a ship 1 including a hull 2. Of course, the hull 2 may be of any suitable dimensions and material. The sides of the hull 2 are provided, in the bow portion of said hull, with series of openings 3.

Within the hull 2, adjacent the openings 3, is a substantially anticlinal deck 4. Fuel tanks 5 are provided below the deck 4. Below the fuel tanks 5, ballast tanks or chambers 6 are provided.

Standards 7 rise from the axis portion of the deck 4. Longitudinal shafts 8 are fixed on the standards 7. Transversely extending platforms 9 are mounted, at an intermediate point, for rocking movement in a vertical plane on the shafts 8. Toward this end, the platforms 9 include depending bearings 10 which are journaled on the shafts 8. Opposed, coaxial disks 11 are fixed on the

shafts 8 and the platforms 9. The pairs of disks 11 have formed therein openings 12 for registry with each other. Pins 13 are insertable selectively in the registering openings 12 for releasably securing the platforms 9 against rocking or swinging movement on the shafts 8.

The platforms 9 are adapted to support and launch boats 14. Toward this end, the platforms 9 further include rollers 15 and opposed guides 16 adjacent the ends of said rollers. Cradles 17, for the boats 14, travel on the rollers 15 in the guides 16. Chains 18 releasably connect the boats 14 to the platforms 9. Platforms 19 on the deck 4 facilitate getting into and out of the boats 14.

Mounted longitudinally in the side portions of the hull 2, above the boats 14 on the platforms 9, is a pair of tracks 20 in the form of I beams. A transverse crane 21 is operable on the tracks 20. The crane 21 comprises an inverted channel iron 22 having fixed on its ends carriages 23, said carriages including rollers 24 which travel on the tracks 20. Fixed on the side portions of the channel iron 22 and depending therefrom in parallelism therewith is a pair of opposed channel guide members 25 having rollers 26 mounted in their lower portions. A boom 27 in the form of an I beam is operable on the rollers 26 between the guides 25. A carriage 28 is operable on the boom 27. Coacting stops 29 on the channel iron 22 and the boom 27 limit the travel of the latter. Stops 30 for a similar purpose are provided on the boom 27 for the carriage 28. Rollers 31 on the boom 27, outwardly of the stops 29 thereon, travel beneath the channel member 22 for preventing said boom from binding thereon.

It is thought that the operation of the invention will be readily apparent from a consideration of the foregoing. Briefly, to launch the boats 14, the chains 18 are released and the pins 13 are withdrawn. Thus, the platforms may be rocked on the shafts 8 to an inclined position for launching the boats through either of the openings 3, the platforms 9 traveling by gravity on the rollers 15. Stops 32 on the guides 20 bring the cradles 17 to a sudden stop and the boats 14 slide by momentum and gravity from said cradles into the water.

In the embodiment shown, the boats 14 are of the protective or combat type. These boats are of any suitable construction, and they may carry on their sterns a plurality of depth bombs, as at 33. These boats may also include any suitable arrangement of air chambers for righting them

in the event they should capsize when launched. To recover the boats 14, the boom 25 is projected laterally through the desired opening 3 over the water, as suggested in broken lines in Figure 4 of the drawings. The boats 14 are then lifted out of the water by means including a suitable block and tackle arrangement suspended from the carriage 28. The crane 19 may be manually or power operated. If desired, the openings 3 may be closed in any suitable manner. The construction and arrangement, it will be observed, is such that the boats may be launched and recovered on either side of the hull 2.

It is believed that the many advantages of a ship constructed in accordance with the present invention will be readily understood, and although a preferred embodiment of the vessel is as illustrated and described, it is to be understood that changes in the details of construction and in the combination and arrangement of parts may be resorted to which will fall within the scope of the invention as claimed.

What is claimed is:

A ship comprising a hull having transversely aligned openings in its sides, a substantially anticinal deck in the hull between the openings, standards rising from the longitudinal axis of the deck, a shaft fixed on the standards and paralleling said longitudinal axis of the deck, a platform pivotally mounted, at an intermediate point, for rocking movement in opposite directions and 10 in a vertical plane on the shaft, said platform including rollers and a pair of guides, a cradle, for supporting a boat and for launching said boat through either of the openings, operable on the rollers in the guides, and means for releasably 15 securing the platform against rocking movement on the shaft, said means including opposed, coaxial disks fixed on the platform and the shaft, said disks having openings therein for registry with each other, and a pin insertible in the registering openings.

THOMAS BOYLE.
